UNITED STATES PATENT OFFICE.

HENRY B. MACE, OF ERDENHEIM, PENNSYLVANIA.

TOOL-HOLDER.

1,128,165.

Specification of Letters Patent.

Patented Feb. 9, 1915.

Application filed March 18, 1914. Serial No. 825,621.

To all whom it may concern:

Be it known that I, HENRY B. MACE, a citizen of the United States of America, residing at Erdenheim P. O., in the county of Montgomery and State of Pennsylvania, have invented new and useful Improvements in Tool-Holders, of which the following is a specification.

The invention relates to tool holders, one of the main objects being to provide a holder, having means associated therewith to make possible the ready insertion and positive maintenance of a tool in a fixed position therein, so that the same may be readily adapted for use.

Another object of the device is to provide a tool holder, having a tool receiving recess in one end thereof, and a pin passing through said recess to engage a hooked terminal of said tool.

A still further object is to provide a tool holder, having a latch pivotally mounted therein to coöperate with a side of the tool, to cause the latter to be held in a locked position within said holder.

Still further objects will appear as the invention is more thoroughly disclosed in the following description when taken in conjunction with the accompanying drawing.

Figure 1 is a perspective view of a device comprising the preferred embodiment of the invention and illustrating a tool of the screwdriver type attached thereto. Fig. 2 is a diametrical horizontal sectional view taken through a portion of the holder in the position shown in Fig. 1 and also showing the method of attaching a tool thereto, the initial position of the tool being shown in dotted lines and the normal operation position in full lines; Fig. 3 is a transverse sectional view through the device; and Fig. 4 is a detail view of the tool locking means.

Referring more particularly to the accompanying drawing, a tool holder A is provided with the usual handle portion 1 and at its opposite end with the tool engaging portion 1', the latter portion being provided with a recess or slot 2, through which passes a pin 3 extending vertically through said slot and being fixedly mounted within said holder A.

A tool 4 is adapted to be fastened in a fixed position in relation to the holder by passing a hooked terminal 5 around the pin 3, as shown in dotted lines in Fig. 2, and then swinging the same about the axis

formed by said pin, until it comes into contact with the wall 7 forming the innermost extremity of said slot.

A latch lever 8 is pivotally mounted in a recess 10, having its longitudinal axis lying parallel with the pin 3, and extending inwardly from the terminal 1' of the handle A. Formed integral with said latch lever is a head 11, offset laterally from the body of the lever, so as to provide a relatively large frictional bearing surface 12, said bearing surface lying in a depression 13 in one side of the handle 1 and adjacent to its end 1'. Said depression forms a part of the recess 10, and the lever in this position engages the sides of the recess 13 to effectively hold the former in a locked position.

It will be obvious upon reference to the drawing, that a side of the lever 8 engages the tool 4, holding the same in firm frictional contact against the innermost wall 7 of the slot 2, and thereby holding the tool locked against any accidental displacement at the same time allowing said tool to be quickly and readily adapted for use. The latch lever 8 is further provided on its head 11 with a knurled surface 14, to permit a ready shifting of the same to an unlocked position upon the exertion of pressure thereupon by the thumb of the operator.

While the description discloses the preferred form of the invention, it will be understood that from time to time such structural changes may be made in the device as practice may disclose, but such changes will be limited to the scope of the claims hereunto appended.

I claim:

1. The combination with a tool having a hooked end, of a holder for said tool, said holder having one of its ends provided with a longitudinally extending slot that opens to one of its sides and which has its rear wall provided with a depression, a pin passing transversely through the said depression and adapted to receive the hooked end of the tool to permit the shank of the tool resting against the rear wall of the depression, a latch member pivotally secured to the end of the holder and adapted to be swung transverse of the depression to engage with the tool to force the same into frictional contact with the rear wall of the depression.

2. The combination with a tool having a hooked end, of a holder for said tool, said

holder having a longitudinally arranged slot, a pin passing transversely through the slot to receive the hooked end of the tool, to permit the shank of the tool resting against the rear wall of the slot, said holder having its end provided with a recess arranged at a right angle to the slot passing through the said slot, a latch arranged within the recess and having one of its ends 10 pivotally secured therein, said latch having its opposite end provided with a lateral

knurled head and the holder having a depression to receive the said head when the latch is swung across the slot to engage with the shank of the tool to force the said 15 shank against the inner wall of the slot.

In testimony whereof I affix my signature in presence of two witnesses.

HARRY B. MACE.
